DESIGN FOR A SHOE

Nathan Kenneth Kean, New York, N. Y.

Application December 24, 1934, Serial No. 54,581

Term of patent 3½ years

To all whom it may concern:

Be it known that I, Nathan Kenneth Kean, a citizen of the United States, residing in New York, in the county of New York, in the State of New York, have invented a new, original, and ornamental Design for a Shoe, of which the following is a specification, reference being had to the accompanying drawing, forming part thereof;

I claim:

The ornamental design for a shoe as shown.

NATHAN KENNETH KEAN.
